(57) **CLAIM**

The ornamental design for a wine container, as shown and described.

DESCRIPTION

FIG. 1 is a perspective view of a wine container showing my new design;

FIG. 2 is a front elevation view thereof;

FIG. 3 is a rear elevation view thereof;

FIG. 4 is a right side elevation view thereof;

FIG. 5 is left side elevation view thereof;

FIG. 6 is a top plan view thereof; and,

FIG. 7 is a bottom plan view thereof.

In the drawings, the stippled shading represents portions of the container surface having a contrast in appearance.
